FIRE FIGHTING AND RUNWAY FOAM SPREADER MODULE

John C. Gibson, Lawrence, Mass., assignor to Gibson Motor and Machine Service, Inc., Lawrence, Mass.

Filed Feb. 14, 1974, Ser. No. 442,576

Term of patent 14 years

Int. Cl. D12—16

U.S. Cl. D12—155

Fig. 1.

Fig. 3.

Fig. 2.

Fig. 4.

Fig. 5.

FIG. 1 is a front elevational view of a fire fighting and runway foam spreader module showing my new design with the foam spreader extended;

FIG. 2 is a front elevational view thereof with the foam spreader compacted;

FIG. 3 is a perspective view taken from the top, front and one side of FIG. 2;

FIG. 4 is an elevational view of the side shown in FIG. 3; and

FIG. 5 is a rear elevational view of FIG. 2.

I claim:

The ornamental design for a fire fighting and runway foam spreader module, as shown and described.
